UNITED STATES PATENT OFFICE.

HARVEY B. HALL, OF HOMER, ILLINOIS.

RAIL TIE AND FASTENER.

1,130,081.

Specification of Letters Patent. Patented Mar. 2, 1915.

Application filed June 25, 1914. Serial No. 847,342.

To all whom it may concern:

Be it known that I, HARVEY B. HALL, a citizen of the United States, residing at Homer, in the county of Champaign and State of Illinois, have invented certain new and useful Improvements in Rail Ties and Fasteners; and I do declare the following to be a full, clear, and exact description of the invention, such as will enable others skilled in the art to which it appertains to make and use the same.

This invention relates to new and useful improvements in rail ties and fasteners and the primary object of the invention is to provide a reinforced concrete tie with means carried thereon for securing the rails thereto without the use of spikes and the like.

A further object of the invention resides in providing a fastening means in connection with the tie which will enable the rails to be adjusted laterally of said tie according to the tread of the object to move thereover.

Still another object of the invention resides in the provision of a device which is simple and durable in construction, inexpensive to manufacture and one which will be very efficient and useful in operation.

With these and other objects in view my invention consists of the novel features of construction, combination and arrangement of parts as will be hereinafter referred to and more particularly pointed out in the specification and claims.

In the accompanying drawing forming a part of this application: Figure 1 is a plan view of a device constructed in accordance with my invention: Fig. 2 is a front elevation thereof: Fig. 3 is a vertical section therethrough as seen on line 3—3, Fig. 1. Fig. 4 is an end elevation of the device: Fig. 5 is a vertical transverse section as seen on line 5—5, Fig. 3.

In describing the invention I shall refer to the drawing in which similar reference characters designate corresponding parts throughout the several views and in which—

1 designates a metallic shell or casing which is of any desired length and designed preferably rectangular in cross section said shell or casing being filled with a plastic composition indicated at 2 to form a rail tie. Extending longitudinally through the plastic composition 2 forming the body of this tie is a reinforcing bar 3 the ends of which are upturned as shown at 4 to project through the top of the casing 1 at points ad-

jacent the ends thereof. The free ends of these upturned portions 4 of the bar 3 are threaded and engaged with nuts 5 whereby to be used in connection with the rail fastening means which is hereinafter and more particularly set forth.

Formed on or otherwise rigidly secured to the upper face of the shell or casing 1 at points inwardly from the upturned portions 4 are the metal rail clips or clamps 6. These clamps are adapted to receive rails 7 thereagainst in the positioning of said rails on the tie and my invention contemplates the provision also of movable clamps for the engagement of the outer sides of the rails. To this end additional clips or clamps 8 are provided the same being adapted to rest flatly on the upper face of the shell 1, said members 8 being provided with slots 9 through which are disposed the projecting portions of the upturned ends 4 of the bar 3. The inner opposed faces of the clips or clamps 6 and 8 are designed coincident to the outline of the sides of the rails so as to fit the same snugly in the application of the invention to use. It will be appreciated that by the positioning of the clips 8 in connection with the upwardly projecting portions 4, said members 8 may be secured in their adjusted positions by the turning home of the nuts 5. Thus after the rails have been once positioned on the tie against the rigid or immovable clamps or clips 6, the movable clamps or clamps 8 are swung into position against the outer faces of the rails and when fitted thereagainst, said nuts 5 are turned home to bind tightly against the upper faces of said members. It is obvious through this medium that said movable members 8 will be secured in their engaging positions against the rails and in order to positively secure the rails against longitudinal movement set screws 10 are provided in the upper portions of the movable clamps 8. These set screws when turned in the proper directions will bind tightly against the webs of the rails 7, thus positively securing said rails in position on the tie.

The casing 1 which forms the outer portion of the tie proper is provided on its side faces adjacent its end with ears 11 which enable the tie to be secured to adjacent objects in the positioning of said tie in place.

From the foregoing description of the construction of my improved device the

manner of applying the same to use and the operation thereof will be readily understood and it will be seen that I have provided a simple, inexpensive and efficient 5 means for carrying out the objects of the invention.

While I have particularly described the elements best adapted to perform the functions set forth, it is obvious that various 10 changes in form, proportion and in the minor details of construction may be resorted to, within the scope of the appended claims, without departing from the spirit or sacrificing any of the principles of the invention. 15

Having thus described my invention, what I claim is:

1. In a device of the class described, the combination with a plastic body forming 20 a tie; of a bar embedded therein and extending longitudinally thereof, the ends of said bar being bent upwardly to project above the top face of the tie at points adjacent the ends of the latter, clamps rigidly 25 secured to the upper face of the tie inwardly of the upwardly bent ends of said bar, additional clamps movably engaged with the upwardly bent ends of said bar

and means engaged with the last mentioned ends of said bar for securing said additional 30 clamps in various adjusted positions on the tie. 35

2. In a device of the class described, the combination with a tie; of a bar embedded therein and extending longitudinally therethrough, the ends of said bar being bent upwardly to project through the top face of said tie at points adjacent the ends of the latter, said last mentioned ends of the bar being threaded, clamps rigidly secured to 40 the upper face of the tie inwardly of the ends of said bar, additional clamps movably engaged with the upwardly bent ends of said bar, and nuts engaged with the threaded bent ends of said bar and with the 45 upper faces of said additional clamps to secure the latter in various adjusted positions on the tie.

In testimony whereof I have hereunto set my hand in presence of two subscribing witnesses. 50

HARVEY B. HALL.
